CLAIM

The ornamental design for a packaging container, as shown and described.

DESCRIPTION

FIG. 1 is a front view of a packaging container showing my new design;

FIG. 2 is a rear view thereof;

FIG. 3 is a top view thereof;

FIG. 4 is a bottom view thereof;

FIG. 5 is a right-side view, the left-side being a mirror image thereof; and,

FIG. 6 is a sectional view taken along line 6—6 of FIG. 3.

The broken diagonal lines on the drawings indicate translucency.
